UNITED STATES PATENT OFFICE

RANDOLPH MONRO AND JOHN C. GOSHORN, OF EDGEWOOD, MARYLAND

CANISTER

Application filed March 15, 1928. Serial No. 261,965.

(GRANTED UNDER THE ACT OF MARCH 3, 1883, AS AMENDED APRIL 30, 1928; 370 O. G. 757)

The invention described herein may be manufactured and used by or for the Government for government purposes, without the payment to us of any royalty thereon.

5 This invention relates in general to respiratory apparatus, and more particularly has reference to an improved canister for gas masks.

Previous to this time the masks employed 10 in warfare and industry for protection against toxic and noxious gases or smokes have had embodied in their structure certain fundamental disadvantages, generally centering around the canister element that this 15 invention seeks to overcome.

The canisters used prior to this time have not been suitably protected against moisture reaching the contents, either in use or in storage, nor has there been provided adequate 20 shield in their structure to prevent clogging or damaging the intake and outlet valves. The valves customarily used in such canisters have been fixed and in case of defect or for other purposes it has been impossible to 25 easily interchange them. The casings have furthermore been of unstable structure, offering little resistance against bending and thereby liable to function inefficiently when distorted or being rendered totally inoperative 30 when strained to the point of rupture.

There has been no provision in the prior art for compressing the chemicals within the canister to insure greater efficiency of operation, nor have the canisters had partitions of 35 sufficient strength provided between the stratas of chemicals to insure the stable position of the contents without retarding the normal operation.

40 An object of this invention is to provide a canister for respiratory apparatus having provisions for preventing moisture reaching the contents in operation or during storage.

Another object of this invention is to provide 45 a canister for respiratory apparatus having removable intake and outlet mechanisms.

A further object of this invention is to provide 50 a canister for respiratory apparatus having provisions for insuring a rigid structure.

A still further object of this invention is

to provide a canister for respiratory apparatus having provision for preventing the chemicals from interfering with the operation of the intake and outlet mechanisms.

Yet a still further object of this invention 55 is to provide a canister for respiratory apparatus having provisions for uniformly compressing the contents and preventing leakage of the chemicals.

This invention consists in general of the 60 provision of a canister for respiratory apparatus, comprising a casing having a tapered top portion and a threaded neck joined on the top portion, adapted to engage the threaded recess in the valve. The neck is 65 provided with an integral overlapping flange designed to serve the double purpose of reinforcing the structure and acting as a seat for a sleeve adapted to receive an outlet check valve. The bottom of the canister 70 is provided with an aperture having edges forming a seat to receive a sleeve for an intake check valve.

The bottom of the container is provided 75 with a vertical circumferential flange adapted to be telescoped in the casing of the canister. A dome of irregular shape affording equal contact against the edge of the canister bottom is simultaneously held under maximum compression throughout its entire 80 periphery to insure a positive step to prevent collapse of the chemicals against the lower check valve. A circumferential flange is provided in the vertically extending portion of the bottom to act as a retainer for the edges 85 of the dome.

With these and other objects in view which may be incident to the improvements, the invention consists in the parts and combinations to be hereinafter set forth and claimed, 90 with the understanding that the several necessary elements comprising the invention, may be varied in construction, proportions and arrangement, without departing from the spirit and scope of the appended claims. 95

In order to make the invention more clearly understood, there is shown in the accompanying drawings means for carrying the same into practical effect, without limiting the improvements in their useful applica- 100

tions to the particular constructions, which for the purpose of explanation, have been made the subject of illustration.

In the drawings:

5 Figure 1 is a side elevational view of the canister shown mounted in a conventional gas mask;

10 Fig. 2 is a side elevation partly sectional view of the respiratory valve and lower part of the gas mask;

15 Fig. 3 is a side elevation half sectional view of the canister;

20 Fig. 4 is a top plan view of the respiratory valve.

25 Referring by numerals to the drawings wherein the same elements are designated by the same numerals throughout, and more particularly to Fig. 1, there is shown a conventional gas mask, having a usual front portion composed of any suitable substance 1, eye pieces 2, made of glass, or any desirable transparent composition, head straps 3, a centering band 4 for the straps 3, and a back portion 5, joined or continuous with the front portion 1 and made of like material.

Secured to the front portion 1 and the back 5, is a respiratory valve 6. The valve 6 is provided with a peripheral channel 10 adapted to afford a leak-proof connection, and the joint secured by a tape 14 treated with adhesive substance, as shown in Fig. 2. The valve 6 comprises a threaded recess 7, integral deflector tubes 8 and a valve stem 9 adapted to receive a flutter valve 11. The flutter valve 11 is firmly fitted in the stem 9 and the joint made leak-proof by tape 12 treated with adhesive substance.

30 The canister forming the subject matter of this invention comprises a casing having a cylindrical body portion 15 and a tapered top portion 16. Mounted on the tapered top portion 16 is a neck portion 31.

35 The threaded neck 31 is adapted to engage the threaded aperture 7 in the respiratory valve 6, and is provided with an overlapping circumferential flange 32 designed to lend rigidity to the structure. The canister is provided with a bottom portion 34 having a central aperture in which there is seated a sleeve 35. The bottom portion 34 is provided with a vertical circumferential flange 36, adapted to be telescoped in the body portion 15. A circumferential sleeve 35 is formed on the inside of the vertical flange 36. The sleeve 35 is adapted to receive a rubber intake check valve 37 and a check valve flap 38. A cap 39 having perforations to admit the contaminated air is 40 adapted to be fitted in a snap channel 40 provided in the valve sleeve 35.

45 A sleeve 41 is adapted to be seated on the flange 32 on the neck portion 31. The sleeve 41 is designed to receive an outlet rubber check valve 42 having a flap 43.

The canister is loaded at the bottom with a layer of caustic pumice 18 resting on a dome retainer 19. The dome retainer 19 is adapted to contact against the edge of the bottom 34 and be held by the angle member 33. A screen partition 20 is fitted to the canister casing 15 over the pumice, and superimposed on the screen disk is a non-inflammable cloth disk 21. A strata of activated charcoal 22 is placed on the cloth 21 and over the activated charcoal is provided a filtering partition attached to the casing wall 15 comprising a screen disk 23 and a sheet of filtering material 24. Resting on the filtering material 24 is a strata of hopcalite 25. Over the surface 80 of the hopcalite there is a fireproof cloth portion 26, upon which there is superimposed a screen portion 27 attached to the canister wall 15, and a fireproof cloth 28 superimposed over the screens 27. A collar 29 having a shoulder 30 is designed to fit on the cloth 28, the shoulder 30 being adapted to engage the flange 32 on the neck 31.

50 A gasket 44 is adapted to be interposed between the flange 32 of the canister and the respiratory valve 6 when the flange is in engagement with the threaded recess on the valve. A wire 45 is riveted on the gasket 44 across the inlet to prevent the flap 43 from entering the orifice in the tubes 8 during 95 inhalation.

55 The operation of this invention may be readily understood having reference to Figs. 2 and 3. The tubes 8 are adapted to deflect the inhaled air over the eye pieces 2. The wire 45 riveted on the gasket 44 is so placed to prevent the flap 43 on the outlet check valve 42 of the canister from entering the orifice of the tubes and retarding operation.

60 The bottom portion 34 of the canister is 105 adapted to be telescoped in the casing 15 to compress the contents to any desired degree, to obtain the greatest efficiency of operation. The dome retainer 19 secured on the bottom portion 34 by the angle rim 33 is held under maximum compression throughout its entire periphery, to afford a positive step to prevent collapse of the contents against the intake check valve, and also to prevent leakage of the chemicals. The collar 29 in conjunction with the integral shoulder 30 is 110 designed to prevent the contents from clogging the outlet check valve.

65 The chemicals shown as embodied in the container have been found in practice to have the most efficient action when incorporated in the following proportions:

Caustic pumice	100 c. c.
Charcoal	90 c. c.
Hopcalite	130 c. c.

70 It is to be distinctly understood that this invention is not limited to the chemicals shown or the proportions named as they are 75 illustrated solely as an example, and neither 80 85 90 95 100 105 110 115 120 125 130

is the invention restricted to any particular number of stratas of chemicals, or partitions, or the materials of which the partitions are composed, for it is obvious that canisters are loaded to suit particular requirements and in fact is one of the primary advantages of this invention that the canister may be loaded with the greatest ease and rapidity.

10 The canister is protected against moisture reaching the contents either during use or in storage by the rubber intake and outlet mechanism protected from clogging by the contents. The intake and outlet mechanism are placed in the canister to allow ready removal for inspection or substitution. The body of the canister is made rigid by integral supports and is provided with a telescopic bottom to allow compression of the contents.

15 20 While we have shown and described the preferred embodiment of the invention, it is to be understood that we do not confine ourselves to the precise details of construction herein set forth, by way of illustration, as 25 it is apparent that many changes and variations may be made therein, by those skilled in the art, without departing from the spirit of the invention, or exceeding the scope of the appended claims.

30 We claim:

1. In a canister for a respiratory apparatus, a casing having a body portion, a bottom portion, a top having a reinforced neck adapted to engage a member on the respiratory apparatus, and means carried by the neck to support a check valve mechanism.
2. In a canister for a respiratory apparatus, a casing having a body portion, a bottom adapted to seat a check valve, a top having a reinforced neck adapted to engage a member on the respiratory apparatus and a sleeve mounted on the neck to support a check valve mechanism.
3. In a canister for a respiratory apparatus, a casing, a neck having a reinforcing flange mounted on the casing, means on the neck to support a check valve, and means projecting against the reinforcing flange to prevent clogging of the check valve.
4. In a canister for a respiratory apparatus, a unitary lower end structure comprising a bottom portion formed with a vertical circumferential flange, a dome retainer adapted to contact with the edge of the bottom portion, and an angle member adapted to fit within said flange and secure said dome retainer to said bottom portion.

In testimony whereof we affix our signatures.

60
